(57) **CLAIM**

We claim the ornamental design for a base for an emergency fixture and faucet set, as shown and described.

DESCRIPTION

FIG. 1 is a front, right perspective view of the claimed design of a base for an emergency fixture and faucet set; FIG. 2 is a front, right perspective view of the claimed design, drawn without environmental features;

FIG. 3 is a front view of the claimed design of FIG. 2;

FIG. 4 is a rear view of the claimed design of FIG. 2;

FIG. 5 is a left view of the claimed design of FIG. 2;

FIG. 6 is a right view of the claimed design of FIG. 2; and,

FIG. 7 is a top view of the claimed design of FIG. 2.

The broken lines shown in FIG. 1 depict environmental structure. The remaining broken lines depict portions of the base for an emergency fixture and faucet set. None of the broken lines shown in the figures form part of the claimed design.
